UNITED STATES PATENT OFFICE.

ALEXANDER P. MOORE, OF CHICAGO, ILLINOIS.

DESIGN FOR A BOTTLE.

SPECIFICATION forming part of Design No. 21,238, dated December 15, 1891.

Application filed July 29, 1891. Serial No. 401,080. Term of patent 14 years.

To all whom it may concern:

Be it known that I, ALEXANDER P. MOORE, a citizen of the United States, residing at Chicago, in the county of Cook and State of Illinois, have invented and produced a new and original Design for Bottles, of which the following is a specification, reference being had to the accompanying drawings, forming part thereof.

Figure 1 is a perspective view of a bottle, showing my design. Fig. 2 is an end view of said bottle, and Fig. 3 a rear view.

The leading feature of my design consists in a bottle having the shape of a United States mail-box, with the representation of the letter-slot, hasp, padlock, &c., of a mail-box blown in the bottle.

A indicates the bottle, the body A' whereof is rectangular in its general shape and its four

sides flat to correspond with the shape of a mail-box. The side A² has a slight depression a near its upper end to represent a letter-slot, while the opposite side A³ has formed thereon a ridge a', hasp a², staple a³, and padlock a⁴. The letters "U. S." and "M L" are blown in said side A³, as shown. A tapering neck B joins the curved cover or top of the body of the bottle. The front and rear sides A⁴ A⁵ of the bottle have their outer surfaces slightly depressed, as shown at b.

30

What I claim is—

The design for a bottle, substantially as herein shown and described.

ALEXANDER P. MOORE.
